UNITED STATES PATENT OFFICE.

WILLIAM F. PHILLIPP, OF YANTIC, CONNECTICUT.

CHIMNEY ATTACHMENT.

Application filed July 10, 1926. Serial No. 121,613.

The invention relates to protective and draft regulating means for chimneys and smoke flues generally, to prevent fire and counter currents.

The invention provides an appliance, which is designed to be located within the chimney opposite the opening receiving the smoke pipe from the stove or furnace, to arrest sparks and break up flame and the products of combustion and thereby prevent soot collecting on the walls of the chimney or flue.

While the drawings illustrate a preferred embodiment of the invention it is to be understood that in adapting the means to meet specific needs and requirements, the design may be varied and such other changes in the minor details of construction may be resorted to within the scope of the invention as claimed without departing from the spirit thereof.

For a full understanding of the invention and the merits thereof, reference is to be had to the following description and the drawings hereto attached, in which,—

Figure 1 is a sectional view illustrative of the invention,

Figure 2 is a view of the attachment as seen from the bottom side, the tapering collar being in section, as indicated by the dotted lines 2—2 of Figure 1, and

Figure 3 is a detail view of a portion of the deflector.

Corresponding and like parts are referred to in the following description and designated in the several views of the drawings by like reference characters.

The numeral 1 designates a chimney or smoke flue and 2 a smoke pipe connected thereto and leading from a stove or furnace in a manner readily understood. The delivery end of the smoke pipe 2 connects with the usual opening 3 of the chimney or smoke flue.

The attachment comprises an anchor 4 which, as shown, consists of a tapered collar which is secured in the opening 3 by a wedging action, and to which the smoke pipe 2 is connected by means of a slip joint. The attachment also comprises a deflector 5 and a baffle 6, the latter serving to connect the deflector 5 with the anchor 4. The deflector 5 consists of a metal plate bent into circular form and disposed with the hollow side facing the smoke pipe, so as to arrest sparks and such particles and prevent the same

from striking the rear wall of the chimney and these particles, if light, ascend with the draft, or if heavy, gravitate and collect at the bottom of the chimney or flue to be removed as occasion may require. The baffle 6 comprises a plurality of spaced elements and is preferably formed from a metal plate bent into circular form and provided with a plurality of longitudinally disposed spaced slots 7. The baffle is disposed with its hollow side facing downwardly and in line with the top side of the opening 3. One end of the baffle 6 is secured to the anchoring collar 4 and the opposite end is made rounding to conform to the hollow side of the deflector 5 and has a tongue 8 which is fast to an opening 9 of the deflector and bent upwardly and apertured to receive a cotter pin 10 or like fastening to hold the deflector in place. The strips or portions separated by the slots 7 constitute breakers which operate to separate or divide the flame, smoke and products of combustion to facilitate the separation of the particles, whereby the light matter ascends with the draft and the heavy matter precipitates to the bottom of the chimney or flue.

The deflector 5 is pivotally connected intermediate its ends to the baffle, and this arrangement admits of adjusting the deflector to lie against the baffle, so that the attachment may be readily placed in position by passing the deflector and baffle through the opening 3. The lower end of the deflector 5 is weighted, as indicated at 11, and when the deflector clears the inner wall of the chimney it automatically assumes a vertical position, as indicated most clearly in Figure 1. A tie 12 connects opposite edge portions of the deflector and may serve to limit the movement of the deflector in one direction by engaging opposite edge portions of the baffle. The tie 12 prevents spreading of the deflector and functions as a brace in addition to acting as a stop.

When the attachment is in position it is retained in place by the wedging action of the anchoring collar 4. The baffle 6 is in line with the top portion of the opening 3 and the deflector 5 projects some distance above the opening. By reason of the disposition of the parts, the greater portion of the flame, smoke and products of combustion is directed downwardly by the baffle and caused to escape into the chimney through the lower portion of the opening 3. As a re-

sult sparks and other particles strike the deflector 5 and are directed upwardly or downwardly accordingly as said particles are light or heavy. The spaced elements of the 5 baffle formed by the slots 7 divide and break up the flame and smoke and prevent the flame from striking the inner walls of the chimney in a manner to deposit soot thereon. These elements also operate to prevent back 10 drafts and counter-currents, ordinarily tending to offset the drafts of the stove or furnace when the wind is blowing in a direction to enter the chimney or flue.

Having thus described the invention, I 15 claim:

1. In combination with a chimney having an opening to receive a smoke pipe, a baffle disposed within the chimney about in line with the upper portion of the smoke pipe 20 opening and a deflector disposed lengthwise of the chimney and free of the walls thereof, and pivoted to the end of the baffle.

2. A chimney attachment comprising an anchoring member adapted to be secured 25 within the stove-pipe opening, a baffle projecting from the upper portion of the anchoring member, and a deflector pivoted in-

termediate its ends to the baffle and normally occupying a position at a right angle thereto.

3. A chimney attachment comprising an anchoring member, a baffle comprising a plate secured at one end to the anchoring member and having its opposite end made rounding and provided with an outwardly disposed tongue, said plate being of circular outline and formed with a plurality of slots, and a weighted deflector pivotally mounted upon said tongue and of circular outline and arranged with the hollow side 30 facing the anchoring member.

4. A chimney attachment comprising an anchoring member, a baffle connected at one end to the anchoring member, a weighted deflector pivotally mounted upon the opposite end of the baffle, and of circular outline and disposed with the hollow side facing the anchoring member, and a tie connecting opposite edge portions of the deflector and adapted to engage the baffle and limit the 45 pivotal movement of the deflector in one direction.

In testimony whereof I affix my signature.

WILLIAM F. PHILLIPP. [L. s.]
